UNITED STATES PATENT OFFICE

2,327,725

SELF-FEEDING EXTRUDER

Lon London, Burley, Idaho

Application June 16, 1942, Serial No. 447,297

1 Claim. (Cl. 146—174)

This invention relates to new and useful improvements in extruders, the principal object of the invention being to provide an extruder which will afford uniform pressure on the material at all times and will eliminate the necessity for the use of a scroll or similar appliance.

Other objects and advantages of the invention will become apparent to the reader of the following description.

In the drawings:

Figure 1 represent a top plan view.

Figure 2 is a side elevational view.

Figure 3 is a vertical sectional view on the line 3—3 of Figure 1.

Figure 4 is a fragmentary detailed sectional view taken substantially on the line 4—4 of Figure 3.

Figure 5 is a fragmentary perspective view of the swingable wall.

Referring to the drawings wherein like numerals designate like parts, it can be seen that numeral 5 denotes a bin-like structure having a back wall, side walls, and a bottom wall. The bottom wall is in the form of a sieve 6 which extends from a point at the lower edge of the swingable back wall 7, to the point 8 at the lower edge of the front wall 9 and well above a roll 10 which is located within the lower portion of the bin. This roll comprises a cylinder 11, flanged at its end portions as at 12 and having rods 13 extending along the cylinder 11 between said flanges 12. The roll is mounted on a shaft 14 which extends through the side walls of the bin, and of course, is operated by suitable power. As is clearly shown in Figure 3, the roll is situated just above the lowermost portion of the sieve 6 and toward the lower portion of the adjustable back wall 7. This back wall 7 is mounted on hinges

or pivot points 15 and has link bars 16 extending therefrom to short slots 17 in the side walls of the bin. In these slots 17 posts 18 are slidably and equipped with wing nuts 19 which can be tightened to hold the wall 7 in adjusted position.

Above the back wall 7 is a chute structure 20 which allows material to gradually feed onto the roll 10.

Numeral 21 denotes a base frame from which 10 rises post 22 supporting the bin and chute 20.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

An extruder of the class described comprising 20 a bin-like structure provided with a porous bottom wall, an extruding roll mounted within the lower portion of the bin-like structure and toward one side wall thereof, said one side wall being provided with an adjustable panel hingedly 25 secured at its upper portion to the bin-like structure, said panel being provided with ears at its end portions, a link member for each ear, each of said link members being pivotally secured to the corresponding ear, and being apertured at 30 its opposite end, said bin-like structure including end walls formed with substantially horizontal slots, and detent elements disposed through the openings in the link members and through the slots and being adapted to be clamped against the said end walls to hold the link members and the panel in definitely adjusted relation with respect to the roll.

LON LONDON.
